UNITED STATES PATENT OFFICE.

PAUL A. KNAPPE, OF SANTA ROSA, CALIFORNIA.

DESIGN FOR A COMBINED HAMMOCK SEAT AND FRAME.

Application filed April 16, 1928. Serial No. 26,328. Term of patent 3½ years.

To all whom it may concern:

Be it known that I, PAUL A. KNAPPE, a citizen of the United States of America, residing at Santa Rosa, in the county of Sonoma and State of California, have invented a new, original, and ornamental Design for a Combined Hammock Seat and Frame, of which the following is a specification, reference being had to the accompanying drawing, forming a part thereof.

Figure 1 is a perspective view of the article showing my new design, and

Figure 2 is a top plan view of the same.

I claim:

The ornamental design for a combined hammock seat and frame substantially as shown.

PAUL A. KNAPPE.
